UNITED STATES PATENT OFFICE.

CARL ENGBERG, OF ST. JOSEPH, MICHIGAN, ASSIGNOR TO THE AMERICAN MERCANTILE COMPANY, OF DAYTON, OHIO.

MACHINE FOR MAKING DISHES OR TRAYS FROM VENEER-WOOD.

SPECIFICATION forming part of Letters Patent No. 664,540, dated December 25, 1900.

Application filed March 7, 1900. Serial No. 7,658. (No model.)

To all whom it may concern:

Be it known that I, CARL ENGBERG, a citizen of the United States, residing at St. Joseph, in the county of Berrien and State of Michigan, 5 have invented certain new and useful Improvements in Machines for Manufacturing Dishes or Trays from Veneer-Wood, of which the following is a full, clear, and exact description, reference being had to the accompanying 10 drawings, which form part of this specification.

My invention relates to certain improved features of machines for manufacturing dishes or trays from veneer-wood, by reason 15 of which the construction and operation of said machines is simplified.

More particularly, my invention relates to certain novel features in the construction of the wire-stapling device, to an improved manner of mounting and operating the dies whereby the number and extent of wearing-surfaces is reduced, to a novel method of operating the feed of the veneer-wood whereby said feed may be regulated to make any size 25 of dish, and to certain other novelties in adjustment and operation, which will appear more fully in the following detailed description and in the claims.

In the accompanying drawings, Figure 1 is 30 a front elevation of my improved machine. Fig. 2 is a side elevation looking at the left of Fig. 1. Fig. 3 is a section of Fig. 1 on line 3 3. The stapling device is left out of Figs. 2 and 3 for clearness and also because it is shown 35 up fully in the other figures. Fig. 4 is a rear view of the feeding device. Fig. 5 is a detail of the mechanism for operating the feed of the wire for stapling. Fig. 6 is a front view of the wire-stapling device. Fig. 7 is a longitudinal section of same through the middle; Fig. 8, a plan view of same; Fig. 9, a detail of staple forming and driving slides; Fig. 10, a cross-section of the shell for carrying said slides; Fig. 11, a detail of the mechanism for 40 operating the stapling device; Figs. 12 and 14, details of the wire-feeding mechanism. Fig. 13 shows two details of the staple-clenching mechanism.

A A indicate the main frame of the machine, braced at the bottom by the cross-pieces A' A' and carrying at the top the bed-plate B,

upon which are cut and scored the dish-forming blanks.

C is the main driving-shaft, carrying the driving-pulley D, the fly-wheel D', and the 55 several cams for operating the machine, all of which will be described later in detail.

The frame of the machine is provided at each side with guides E' E', beveled at the edge, in which travel the slides E, carrying 60 at their upper ends the knife-bearing cross-head F. Secured to the cross-head in any suitable manner are the usual scoring and cutting knives G for forming the blank; but as there is nothing new about them further 65 description of them is unnecessary. A reciprocating motion is imparted to the slides E E by the arms H H, pinioned to said slides at one end at H' and having their other ends provided with a loop which embraces the eccentric cams H'' H'', which are mounted on the driving-shaft C.

A standard I, bolted to the frame of the machine, carries the mechanism for feeding the veneer-wood. Loosely mounted in this 75 standard is a rock-shaft J, which has rigidly secured to its opposite ends in any convenient manner the arms K and K'. A link L, pivotally connected to the arm K at one end and at the other end attached to the loop M, 80 embracing the eccentric cam M', mounted on the shaft C, imparts an oscillating movement to the arm K, which causes the shaft J to rock, thus oscillating backward and forward the arm K'. Carried by the standard I is a 85 shell I', supporting loosely the sliding bar J', which has pivotally connected to its forward end the presser-foot J'', held down by the spring J'''. A link K'', pivotally connected at one end to the arm K' and at the other to 90 the sliding bar J', transmits the backward-and-forward motion of the arm K' to the sliding bar J', and the sliding bar J'' through the presser-foot J''' in its forward movement feeds the necessary amount of veneer-wood to make 95 a dish. It will be observed that the arm K is provided with a slot O, and it is by means of this slot that the rate of feed of the veneer-wood is varied. The link L is pivotally connected to the arm K by means of the pin 100 O', passing through the slot O, and this pin is held at any point in the slot O by the nut

O". Moving the pin O' nearer to the rock-shaft J has the effect of shortening the arm K. Now as the throw of the eccentric cam M' is always the same the length of arc 5 through which the pin O' travels must always be the same; but as the radius of the arc is decreased by moving the pin O' nearer the rock-shaft J the angle measured by said arc is increased, thus increasing the throw of 10 the arm K', and hence the amount of veneer-wood fed by each forward movement of the presser-foot J". A long double spring-wire P, pivoted at P' and held down by a small coil-spring P", holds the veneer-wood in contact with the bed-plate B and prevents it 15 from sliding backward as the presser-foot J" is dragged back to take hold and feed again. The presser-foot J" is provided with the usual teeth for gripping the veneer-wood. The bar 20 J' is provided with a number of holes Q' for adjusting the position of said bar J' with reference to the knives G.

As the veneer is fed by the mechanism described above the knife-bearing cross-head F 25 descends and properly cuts and scores the dish-forming blank in the usual manner. To assist the return of the cross-head to rise again in readiness to cut the next blank, a pin R is provided, secured at its upper end 30 to the slide E, as seen in Fig. 3, with its lower end passing through a hole in an offset R" of the frame A. A coil-spring R', extending between the head of the pin R and the offset R", is compressed by the descent of the slide 35 E, and when the slide E starts up again its rise is assisted by the elasticity of the spring R'. A like pin R and spring R' are provided on the opposite side of the machine for the other slide E.

40 Next I shall pass to a description of the manner of mounting the dies for forming the dish or tray.

The male die S is carried by the curved arm S', which is pivoted to the back of the 45 frame as follows: The arm S' is in the form of a web, which being of the width of the machine at the rear decreases in front to a width sufficient to give a good bearing to the male die S. This web is strengthened by the ribs 50 S" and S"". The rear end of the arm is circular in section, said section being slightly larger at the center, as seen in Fig. 4. Each end of this circular portion T is provided with a hole or socket into which fit the pins T'. The said pins T' are threaded partly and 55 screwed through the frame of the machine A, so that the bearing of the pins in the socket may be tightened or loosened by simply turning the pins T', and said pins are provided with the clamp-nuts T" for holding 60 them after they have been properly adjusted. It will be observed that the pins T' are slightly pointed, so as to give a true bearing.

The manner above described of mounting 65 the arm S' is the one I prefer, because in this way friction at the fulcrum is reduced to a minimum, there is a minimum of wearing-sur-

face, and any loose play at the fulcrum which may result from wear at the ends of the pins T' may be taken up by a slight turn of said pins. However, as is readily seen, the pins T' 70 may be replaced by a single rod, which would pass completely through the circular part T of the arm S' and be mounted in the frame A. Such method of fulcrumming the arm S' is 75 within the spirit of my invention. The curved arm S' is given an oscillating up-and-down motion in the following manner: Mounted on the shaft C is the eccentric cam C', embraced by the loop or collar C". The collar C" is 80 provided with a lug U, having an internal thread into which works the threaded end of the rod U'. A bifurcated block V is pivoted to an extension V' of the rib S"" and is provided with a smooth socket, into which it receives the upper end of the rod U'. A set-screw U" serves to hold the rod U' in position in the block V, and the nut U''' serves to clamp it at the lower end. It will thus be 85 seen that there is ample means for adjusting the vertical position of the arm S', and therefore of the point of action of the male die. Of course any convenient manner of imparting the motion of the cam C' to the arm S' will answer, and I do not wish to limit myself 90 to the particular construction shown.

The female die W is yieldingly supported in the frame W', which is bolted to the knife-bearing cross-heads F, and as the manner of mounting said female die is readily seen from the drawings and is not new I shall not describe it further, except as to the following: There is provided a finger a, carried on the rod a', for properly overlapping the ends of the dish; but instead of descending with the male die after the dish has been formed, as formerly, it is held out of the way as follows: The rod a' has attached to its upper end the short bar a'', carrying the rod b, which passes through a hole in the frame W'. Pivoted to the frame W' at b' is a Z-shaped bar b'', and a rod c, pivotally mounted at its lower end on the shaft c', (which carries the wire-feeding mechanism, to be described later,) is pivotally attached at its upper end to the Z-shaped bar b'' at c'. The operation is as follows: As the male die ascends it catches the dish-forming blank coming from the knives, carries it up with it, and also the finger a, which causes the blank to fold properly. Now as the male die descends the natural tendency of the finger a is to descend with it; but while the dish was being formed the cross-head F has been rising preparatory to cutting another blank and with it the frame W', which 110 raised the point b', and thus caused the lower end b''' of the Z-shaped bar b'' to come under the rod b and support it. The rod b is thus supported until the male die has descended, when the cross-head F, descending to cut another blank, causes the point b' to descend, and thus rotate the Z-shaped bar b' out of the way of the rod b. This allows the finger a to 115 descend in readiness to fold the next blank.

The mechanism for stapling the blanks is in duplicate, as usual, a like mechanism being mounted on both sides of the machine, as is seen in Fig. 1, where I have lettered this 5 mechanism generally X, special details of it being shown in Figs. 6, 7, 8, 9, and 10.

The staple forming and driving slides are mounted in a shell *d*, which is bolted to an angle-plate *e*′, secured to the top of the frame 10 *A* of the machine. A face-plate *e* is removably secured to the shell *d* by screws or bolts to enable the staple driving and forming slides to be readily got at. The wire for forming the staples is fed through the tube *d*′, 15 which is formed on the shell *d*, into and partly through a transverse slot *f* in the head-block *f* of the rocking bar *f*′, which is rockingly journaled on pin *f*′′, having bearing in the downward-extending flanges *g* *g* of the shell 20 *d*. This head-block *f* is normally held in contact with the face-plate *e*, in position to receive the wire as it comes from the tube *d*′, by a coil-spring *g*′, mounted in sockets in the rocking bar *f*′ and the bottom of the shell. 25 *h* represents the slide by which the wire held by the head-block *f* is cut and bent to form the staple.

i represents the staple-driving slide, which carries at its upper end on its lower side the 30 bifurcated block *j* and on its upper side the standards *k* *k*, in which are journaled the detent *k*′, which normally engages the upper end of the staple-forming slide *h*. The face-plate *e* is cut away at the top, as seen in Fig. 35 8, and has its two extending ends *e*′ beveled, and as the staple-driving slide *i* descends pins *k*′′, extending on each side of the detent *k*′, strike these beveled ends *e*′, and in so doing raise the detent from its contact with the upper 40 end of the staple-forming slide *h*, and thus allow the staple-driving slide *i* to descend by itself. A coil-spring *k*′′ at the upper end of the detent *k*′ tends to hold it in contact with the upper end of the staple-forming slide *h*. 45 The bifurcated block *j* has journaled at its lower end a roller *l*, and as the staple-driving slide descends this roller *l* strikes the upper end of the rocking arm, and thus causes the head-block *f* to drop out of the way of the descending staple-driving slide *i*. The staple-driving slide *i* near its upper end is provided 50 with a slot *i*′, through which passes the bolt *m*. Said bolt *m* is screwed into the upper end of the staple-forming slide *h* and has its head threaded for the entrance of a screw on the end of the pin *n*, which passes loosely through a hole in the block *j*. A coil-spring *n*′ is mounted on the pin *n* between the block *j* and the head *m* of the nut *m*. The purpose of the 55 spring *n*′ is to return the staple-forming slide *h* to its normal position with reference to the staple-driving slide after the staple has been driven. Its tension may be regulated by turning the pin *n*, which is provided with a head *n*′ for that purpose.

The mechanism for operating the staple forming and driving slides is as follows: *o* is

a bell-crank pinioned to the plate *e*′ at *o* and having pivoted to its opposite ends the screw-threaded blocks *p* and *q*. A rod *p*′ is screwed 70 into the block *p* and has its upper end attached to the block *r* by a set-screw *r*′, said block *r* being pivoted in the bifurcated block *j* at *j*′. The head of the rod *p*′ is provided with holes *p*′′ for the admission of an adjusting-pin, by 75 means of which the distance between the pivotal points *j*′ and *p*′′ may be varied, thus varying the force of the impact of the staple as it is driven against the dish-forming blank. A connecting-rod *q*′ is screwed at one end into the block *q* and at the other into a block *q*′′, which is pivotally connected with the crank *s*, rigidly secured to the shaft *s*′. An arm *t* is keyed to the shaft *s*′ in any convenient manner and carries at its lower end a pin *t*′, 80 which works in a groove *t*′ in the face of the cam *u*. (See Figs. 1 and 11.) The groove *t*′ is of such shape that the shaft *s*′ is rocked through the pin *t*′ and arm *t*, and this rocking motion of the shaft *s*′, through the arm *s*, 85 imparts an oscillating motion to the rod *q*′′, which in turn rocks the bell-crank lever *o*, and thus operates the staple forming and driving slides.

The wire is fed to the tubes *d*′ by the following mechanism: Bolted to the plates *e* (see Fig. 1) are the frames 11, carrying the sleeves 3 3 and 2 2. A shaft *c*′, journaled in the sleeves 2 2, carries the feeder-wheels 4 4 and the gear-wheels 6 6, said gear-wheels 6 6 meshing with other gear-wheels 7 7, which are mounted on short shafts 8 8, eccentrically and loosely mounted in other shafts 8^a 8^a, (see Fig. 14,) which are journaled in the sleeves 3 3. Springs 9 9 are coiled about said shafts 8^a 8^a, 105 having one end fastened to the shafts 8^a 8^a in any convenient manner and the other end passing down and held by set-screws 10 10. Other feeder-wheels 5 5 are mounted on said shafts 8 8 and hold the staple-forming wire 110 against the feed-wheels 4 4 by reason of the springs 9 9 and the eccentric mounting of said shafts 8 8 in said shafts 8^a 8^a. By turning the shaft *c*′ the two sets of feeder-wheels are turned, and thus feed the wire to the tube 115 *d*′. Blocks 11, mounted on extensions 12 from the sleeves 2 3, are provided with holes through which the wire passes to the feeder-wheels. The coils of wire for making the staples may be supported in any convenient manner. 120

The mechanism for intermittently turning the shaft *c*′ is shown in Figs. 5 and 12. This consists of the link 13, pivoted to the upper end of the arm *E*, (on the right-hand side of the machine,) and having its other end pivoted to the lever 14, which has one end pivoted at 16 to the frame of the machine and its other end pivoted to the link 18. The link 18 has its upper end pivoted to an arm 19, which is loosely mounted on the shaft *c*′ and carries a pawl 20, held in engagement by a spring 22 with a ratchet-wheel 21, rigidly secured to the shaft *c*′. It will be readily seen that as the arm *E* oscillates up and down it will, 125 130

through the link 13, the lever 14, and link 18, cause the arm 19 to oscillate up and down, and thus turn the shaft 'c' and with it the feeder-wheels 4 and 5. Of course it is only the downward movement of the arm 19 that is operative, as during the upward movement of said arm the pawl 20 simply slides over the ratchet-wheel.

Fig. 13 shows the device for clenching the staples. On each side of the male die is a slot covered by the plate 25, within which slot works the clenching mechanism. A short bar 27 is bolted to the inside of this plate and has rigidly secured to it the pins 28, slightly hollowed out at the top and extending through holes in a second block 27, but not quite through said block. A screw passes loosely through block 26 and is screwed into block 27. Coil-springs 30 surround the pins 28 and normally tend to hold the block 27 with its upper edge slightly above the surface of the die. As the staple-driving slide descends and with it the staples the ends of the staples pass into the holes in the block 27, and as the driver continues to descend it forces the block 27 down and brings the end of the staples forcibly against the ends of the pins 28, which are slightly hollowed out, and thus clenches the staple.

The screw 29 is for regulating the tension of the springs 30.

Having thus described my invention, what I claim as new, and desire to cover by Letters Patent, is—

1. In a dish-forming machine as a means for feeding the veneer, a standard rigidly attached to the rear of the machine, a rock-shaft carried thereby, an arm secured to the said rock-shaft, a slide feeding said veneer, a link connecting said arm and said slide, a second slotted arm secured to said rock-shaft, a shaft and means for operating the same, and operative connections from said shaft to said second arm, and adjustable in the slot thereof, substantially as and for the purpose described.

2. In a dish-forming machine, as a means for feeding the veneer, a spring-controlled finger for gripping the veneer, a rock-shaft, an arm rigidly secured thereto, mechanism intermediate said arm and said finger, whereby said finger is caused to oscillate, a second arm rigidly secured to said rock-shaft, a slot in said second arm, a link pivoted in said slot, and means for operating said link, substantially as shown and described.

3. In a dish-forming machine the combination of a die in two parts, one part rigidly supported in the machine-frame, an arm fulcrumed in the frame, and at its free end carrying the other part of the die, and means for operating said arm, substantially as and for the purpose described.

4. In a dish-forming machine, a female die rigidly supported in the frame, a male die, an arm fulcrumed at one end to the frame and at the other end carrying said male die, a

main driving-shaft, a cam mounted thereon; and mechanism whereby said cam causes said arm to oscillate, substantially as and for the purpose described.

5. In a dish-forming machine, the combination of a main driving-shaft, a cam mounted thereon, a curved arm fulcrumed at the rear of the machine, a male die carried at the forward end of said curved arm, a block pivoted to said curved arm, intermediate the fulcrum and the male die, and a rod adjustably connected to said block and to said cam, whereby said cam causes said curved arm to reciprocate, substantially as and for the purpose described.

6. In a dish-forming machine, a curved arm, a die carried at the forward end of said curved arm, sockets at each side of the rear ends of said curved arm, pins entering said sockets and acting as a fulcrum for said curved arm, a main driving-shaft, a cam mounted thereon, a block pivoted to said curved arm intermediate its two ends, and a rod adjustably connected to said cam and to said block, whereby said cam causes said curved arm to reciprocate, substantially as and for the purpose described.

7. In a dish-former, a female die rigidly supported in the frame, a male die, an arm carrying said male die and fulcrumed at the rear, a block pivoted intermediate said fulcrum and said male die, a cam mounted on a main driving-shaft, a strap on said cam, and a rod adjustable in length connecting said strap and said block, whereby said curved arm is caused to reciprocate, substantially as and for the purpose described.

8. In a dish-former, the combination of a pair of dies, of staple forming and driving mechanism, blocks rigidly supported in one of said dies, and having openings to receive the ends of the staples, and anvils working in said openings and adapted to clench said staples as said blocks are depressed by the staple-driver, substantially as and for the purpose described.

9. In a dish-former, the combination of a pair of dies, of staple forming and driving mechanism, blocks rigidly supported in one of said dies, and having openings to receive the ends of the staples and anvils working in said openings, but fixed relative to the die, and adapted to clench said staples, as said blocks are depressed by the staple-driver, substantially as and for the purpose described.

10. A staple former and driver consisting of a rigidly-mounted shell, a face-plate beveled at its upper end, staple forming and driving slides, arranged to act conjointly to a certain point, a spring-controlled detent carried by said staple-driving slide, and engaging said staple-forming slide up to said predetermined point, extending lugs on said detent adapted to strike the beveled ends of said face-plate, whereby the conjoint action of the slides is discontinued, a spring-controlled staple-retaining block, and mechan-

ism whereby said staple-driving slide is caused to reciprocate, substantially as and for the purpose described.

11. A staple forming and driving mechanism consisting of a rigidly-mounted shell, a face-plate, bifurcated at its upper end, and having said upper ends beveled, staple forming and driving slides arranged to act conjointly to a certain point, a spring-controlled 10 detent carried by said staple-driving slide, and engaging said staple-forming slide up to said predetermined point, extending lugs on said detent adapted to strike the beveled ends of said face-plate, whereby the conjoint action 15 of the slide is discontinued, a spring-controlled staple-retaining block, a roller mounted on said staple-driving slide, whereby said staple-retaining block is caused to release the staple, and mechanism operating said staple-driving

slide, substantially as and for the purpose 20 described.

12. A wire-feeding mechanism consisting of a shaft with means for intermittently turning the same, a disk mounted thereon, a second shaft eccentrically and loosely mounted 25 in a roller, a second disk mounted on said second shaft, gearing intermediate the two shafts whereby they are caused to revolve toward each other, and a coil-spring around said roller, having one end attached to said 30 roller and the other end bearing against the frame supporting said roller, whereby said second disk is pressed against said first disk, substantially as and for the purpose described.
